UNITED STATES PATENT OFFICE

RICHARD F. GILDEHAUS, JR., OF DALLAS, TEXAS

PROCESS OF HEATING OIL FOR DISTILLATION

Application filed June 17, 1925. Serial No. 37,639.

This invention relates to a process for refining oil and to apparatus for carrying out the process, and, broadly, the objects of this invention are to provide an improved process 5 for refining oils, particularly mineral crude oils, and to provide an efficient plant and apparatus for refining oils continuously by means of said process. Obviously in its broader aspects, my invention is applicable 10 to other oils, such as vegetable oils, for example, cotton seed oil. Another object of this invention is to provide a process and apparatus for recovering the lubricating oil fractions in their natural state, uncracked, 15 as they exist in the oil being distilled. A further object of this invention is to provide a process for producing oils of high flash and fire and containing a minimum of carbon forming ingredients, and free of objection- 20 able odor and discoloration, without requiring separate acid treatment. Other objects of this invention will be in part obvious and in part pointed out hereinafter.

It has been found that the heaviest fractions of oils cannot be distilled when heat is applied directly to the still, without partial cracking, even under a high vacuum and with agitation or stirring unless distillation is carried on very slowly. Otherwise local or spot 25 over-heating of the oil occurs, which breaks down the heavy fractions, discolors the distillates and often causes the fractions to carry objectionable odors. If agitation or stirring is increased with a view of preventing 30 cracking while more rapid distillation is attempted, the fractions over-lap, and liquid and carbon pepper are carried over, to an extent depending upon the violence of agitation required for a given rate of distillation. 35 This destroys the effect of the vacuum as regards promoting separation of the fractions, so lowering the flash and fire of each fraction and darkening their colors. In contrast, in my invention there is uniform, smooth, path- 40 flow movement of the oil without violence, at a high velocity where the heat is mainly applied and at a low velocity where the vapors pass out of the liquid. Applying heat indirectly to the still eliminates all over- 45 heating, and, together with positive circula- 50

tion and vacuum, provides means by which rapid heating and distillation may be carried on safely and economically. Such operation under vacuum also causes a more exact separation of the fractions and eliminates all 55 cracking, producing oils of higher flash and fire and with less suspended carbon forming ingredients than could otherwise be produced. Re-running oils under this process produces stable oils of very high color and 60 viscosity, oils as high as 2500 at 100° F. viscosity with a color of No. 1½ N. P. A. having been produced repeatedly without trouble, and where no acid treatment was used to 65 obtain color. Operation shows that with indirect heating and positive circulation without agitation the crude oil can be distilled satisfactorily under vacuums ranging from 25.5 inches of mercury to 29.4 inches of mercury, depending on the gravity of the fractions being distilled; the crude charge under this range of conditions being one that 70 has been stripped of all the light ends, including gas oil. By indirect heating, I mean 75 heating by radiation or convection from the surface of a heat retardant material having a transmission capacity of such value as to prevent the metal heating surface, and consequently the oil in contact therewith, from being subjected to the extremely high fur- 80 nace temperatures.

The lighter fractions down to and includ- 85 ing the cut usually made as gas oil may be taken off uncracked from the treating still or the fractionating still without any vacuum because the heat application is indirect and because the oil may be maintained in positive circulation without agitation, although as a matter of fuel economy a vacuum of 25.5 inches or more is recommended. A vacuum 90 of 25.5 inches or more of mercury is, however, necessary when distilling viscous fractions in order to obtain finer separation and better colors, as previously mentioned. Higher vacuums are required as the heavier fractions 95 are taken off, to reduce their boiling point sufficiently below the critical temperature to avoid cracking; and when combined with indirect application of heat to the still and positive circulation, all danger of cracking the 100

very heavy fractions, each of whose boiling points or temperatures are higher and nearer the critical temperatures, is removed.

By positive circulation, I mean a uniform

5 path-flow movement of the oil through the circuit formed by the still parts maintained by force, by the use of, for example, a force pump connected in the oil circuit; all in contrast with the irregular and turbulent movement which is had with agitation or stirring.

In accordance with this invention, the plant or system for the distillation of oils, particularly mineral crude oils, under vacuum, includes a treating still in which the oil may be 15 maintained in positive circulation during treatment and a fractionating still in which the oil is maintained in positive circulation during distillation, each having a radiant heat combustion chamber where all or nearly 20 all of the recoverable heat of combustion is dissipated through the walls of and then by radiation from the outer surfaces of a series of ducts made of refractory material having a relatively good heat transmission capacity, 25 and is then conducted to the heating surface of the still by a subsequent passage of the cooled gases of combustion around and between the ducts, forming the combustion chamber; combined with condensing and 30 cooling apparatus in two stages, a separating tank, gas cooler, and means for continuously removing the condensate from the separating tank while carrying on fractional distillation under vacuum, consisting of a "dry" vacuum pump to remove any uncondensed vapors and 35 non-condensable gases, and a "wet" vacuum pump to remove and discharge the condensate from the separating tank into open tanks continuously.

40 The condensers are so arranged as to provide a large area of opening from the still into the condensers, so that the gases pass from the still into the condensers at a low velocity, reducing to a minimum the 45 danger of their carrying liquid in suspended form from the still into the condensers. The opening in the condenser is so arranged that the liquid from the gases which are 50 partially condensed, upon entering the condenser, cannot fall back into the still, where they would be again distilled with heavier fractions and so prevent the finer separation which otherwise would take place. It has 55 been found through experiment that where the gases leave the still at a high velocity, they carry over a tar fog, which produces darker colors, the effect depending upon the rapidity of distillation and the velocity of 60 exit. High vacuums expand the gases of distillation to very large volumes, usually requiring large pipe, even with relatively high velocities, and the object of placing the condenser stage immediately upon or 65 closely adjoining the still is to eliminate

the necessity of large pipe lines between the still and condensers.

The condensers may be used to condense practically all of the vapors, the condensate going into the liquid cooler before flowing to the separating tank. However, as shown, the condensate cooler consists of vapor cooling coils as well as run down or liquid cooling coils; liquid condensed in the cooler joining with the liquid from the condensers, both passing through the run down section before entering the separating tank. Here the non-condensable gases and the uncondensed vapors (due to the water temperature and vacuum maintained) are separated from the condensate, the condensate passing down by gravity into the suction side of the "wet" vacuum pump and discharged from it into tanks at atmospheric pressure, as described later. The vapors uncondensed and non-condensable gases are carried through the gas cooler and thence to the "dry" vacuum pump. The gas cooler is supplied with cold water, refrigerated if necessary, to condense the remaining uncondensed vapors as far as practicable, and also to reduce the volume of gases and vapors to be exhausted by the dry vacuum pump. The wet vacuum pump is provided with a speed regulated motor or other speed control drive, so that the speed of the wet vacuum pump can be adjusted to suit the rate of distillation, under which condition it will discharge practically a continuous stream of distillate.

In order that a clearer understanding of my invention may be had, attention is hereby directed to the accompanying drawings, forming a part of this application, and illustrating certain possible embodiments of the invention. Referring to the drawings, Figs. 1 and 1a together complete a diagrammatical top plan view of a plant suitable for carrying out the process, the condensate cooler being omitted for clearness; Figs. 2 and 2a together complete a diagrammatical side view of the same; Fig. 3 is a side view of the treating still and its setting in section, the view being taken on the line 3-3 of Fig. 4; Figs. 4 and 5 are each sectional views of the same, and are taken respectively on the lines 4-4 and 5-5 of Fig. 3; Fig. 6 is a fragmentary view of the same showing a condenser on one of the still outlets; Fig. 7 is a side view of the fractionating still and associated parts of the plant, the still setting being shown in section, the view being taken on the line 7-7 of Fig. 8; Fig. 8 is a sectional view of the same, and is taken on the line 8-8 of Fig. 7; Fig. 9 is an enlarged detail thereof, partly in section, and is taken on the lines 9-9 of Figs. 7 and 8; Fig. 10 is a sectional view of the lower portion of a modified form of fractionating still; and Fig. 11 is an enlarged sectional

view of a fragment thereof, the view being taken on the line 11—11 of Fig. 10. Similar reference characters refer to similar parts throughout the several views of the drawings.

5 Reference will now be made to the drawings.

The crude run

10 Valve 1 admits crude oil to pump A, which discharges the oil through valve 2 into line 14 (valves 3, 4, 5, 6, 7, 8 being closed) and thence into still B. A conventional treating solution consisting of caustic soda and lead oxide is pumped into the still through the 15 line 16, and valve 17, the valves 18 and 19 being closed. Compressed air is admitted through line 11 and valves 11' and 18 to agitate the oil and solution while heat is applied to warm the mix to 212° F. Steam may then 20 be applied for further agitation through the line 10 and valve 10'. After a suitable period of time the mix is then transferred through line 14, valve 8, to pump A, and thence through either valve 5 or 6 to settling tank 25 S or S'. Here the oil is allowed to cool and then it is washed with cold water and permitted to settle. As soon as the treated crude oil has been removed from still B, another 30 charge is made as described while the previous charge has cooled and has been washed.

35 It has been found in treating certain crudes that the treatment is much more effective at high temperatures, requiring pressure to prevent evaporation of the lighter cuts and the treating solution. It also has been found that the treating solution separates more quickly when the mixture of crude and treating solution settles under about the same pressure maintained while treating. To 40 this end I transfer the crude and solution to the settling tanks under pressure, by the use of steam or a non-combustible gas under a range of pressure from 40 to 100 pounds inclusive.

45 The procedure is as follows:

After the crude and solution have been heated and well mixed by pump circulation under pressure, say of 45 pounds, the settling tank S or S', into which the crude and solution are to be transferred, is charged to a corresponding pressure with steam or a non-combustible gas through line 400, valved at 50 401, line 402, valved at 403, and either lines 404 or 405, valved at 406 and 407, depending upon which settling tank S or S' is to be so charged. Then an equalizing line is opened between the top of the settling tank and the domes or one of the domes B' of the treating still B. To provide the equalizing line, a line 408, valved at 409, may join lines 400 and 402, and connect with one or more domes B' of still B through lines 410 and 411. The oil is allowed to flow into the settling tank or is pumped into same, depend-

ing on the relative height of the still and settling tank. Both the still and the settling tanks are provided with adjustable safety valves and pressure regulators (not shown) on the lines 402 and 408, supplying the medium with which pressure is maintained. When the still has been emptied, a new charge 70 may be treated in like manner while the previous charge is settling and cooling.

After settling, the water and sludge is 75 drained from the settling tank and the oil is taken by pump A through valve 7, and charged to the still where it is gradually heated while being agitated with compressed air to thoroughly remove all moisture. The 80 heating here is continued until a temperature of 300° F. is reached, and the oil is held at this temperature until ready for transferring to the fractionating still. The oil may be transferred by pump A through valve 4, line 85 15, and through valves 27 and 25 and thence into header H of the fractionating still O. As the oil is so charged to the fractionating still, the pumps P or P' may be used to circulate the oil in the meantime while heat is 90 being applied. Pump P takes oil from the drum D through valve 24 and discharges same through valve 26 into header H. Instead of transferring the oil with pump A, same may be transferred by either one of the pumps P 95 or P' through the line 14, valve 3, line 15, and either valve 21 or 22, depending upon which of the circulating pumps is used for the purpose of transferring the oil, the alternate pump being used for circulation as already 100 mentioned.

After the transfer has been completed, both pumps P and P' may be used for circulating the oil within the fractionating still. As distillation takes place, the vapors rise in the 105 condensers C, from which the liquid flows in line 38 to the run-down or cooling coils of the cooler E. All vapors not condensed in the condensers C pass out of these condensers through line 36 to the cooler E. The liquid 110 from the cooler E flows into the same run-down coils as the liquid from the condensers coming through the line 38. The liquid from the run-down or cooling coils flows by gravity through line 76, and the vacuum look-box 115 F into the separating tank G. The separating tank G is provided with a gage glass G', so that any accumulation of condensate within the separating tank may be readily observed.

The separating tank is provided with a 120 valved vent 75, and a connection to the dry vacuum pump K, through valves 44 and 45, passing through the gas cooler J. The liquid flows by gravity to the wet vacuum pump Y and is discharged by same into the look-box L, which is provided with a vent-overflow 68 to permit the oil to escape in case valves 52, 53, 54 are closed. From the look-box L the oil is directed into tank M or M' 125 130

through valves 52 and 53, or through valves 54, into the manifold R, and from there directed to a series of tanks T. If the oil is directed to the tanks M and M', it may be transferred from same by pump N through line 72 and valve 78, into manifold R.

The wet vacuum pump Y is provided with a speed regulated drive Y', which is adjusted to the rate of distillation so as to give practically a continuous flow of oil from the discharge of the wet vacuum pump Y, into the look-box L.

The dry vacuum pump K is connected to the gas cooler J, through the valve 45 and line 69, and discharges the non-condensable gases and uncondensed vapors through line 70, into the furnace of the fractionating still. The gas cooler J is provided with cold water circulation (refrigerated, if necessary) through the line 74, valve 42. The water from the gas cooler J passes out through valve 43, into the condenser pan E. The gas cooler J is drained continuously through the valve 48 into a container Q, which is connected to the line 69 by line 77, through valve 47. The container Q is drained by closing valves 47 and 48, and opening valves 49 to admit air, while its contents is removed through valve 50. The gas cooler J is also provided with a by-pass connection through the valve 46 and line 77, so that upon closing valves 44 and 45, the gas cooler J may be opened for cleaning or any other purpose.

Water is supplied through the line 73, and valve 41, to the pan of the condensate cooler E, which is provided with an overflow line 40. The water circulating pump W takes water from the pan of cooler E through line 39 and discharges same through line 37, and the valve 32, 33 and 34, into the condensers C. The discharge water from condensers C flows out of the line 35.

Procedure for various crudes

45 The procedure in detail for handling the crude oil varies, of course, with the nature of the crude itself, but three methods may be outlined in general which will cover practically all mineral crude oils:

50 First: The stripped waxless or coastal crude, or one containing a negligible quantity of wax, is brought from the storage tanks by pump A and discharged into the treating still. Here the necessary treating solution, 55 the conventional mixture of caustic soda and lead oxide, is added and the crude oil gradually heated to 212° F., during which time the oil and treating solution is thoroughly agitated by means of compressed air, supplied 60 through line 11. After being heated for the required time at this temperature, the temperature is increased and the oil and solution are agitated by means of steam supplied through line 10. After suitable period of time, the oil is then transferred to either one

of the settling tanks S or S', where the oil is washed with cold water after having cooled sufficiently, and then allowed to settle, and the sludge and treating solution removed. In the meantime the second charge is placed 70 and treated similarly in the treating still, and thence transferred to the alternate separating tank. The first charge is then pumped back into the treating still after the sludge and water have been removed therefrom in 75 the settling tank. In the still it is gradually heated and agitated with compressed air until all the moisture is driven out, and then the temperature is raised to 300° F. and held at this temperature until ready for transferring to the fractionating still.

While the procedure described above in connection with the treating still has taken place, the previously treated charge of oil has been fractionated in the fractionating 85 still. Here the oil is circulated continuously by means of pump P or P', which takes the oil from the lower rear drum D of the fractionating still and discharges same into the header H connecting the tubes (see Fig. 90 7), and thence through the tubes, the oil then discharging into the upper front drum and rising through the front leg into the still proper. The upper and lower drums are connected so that the oil may pass freely from the upper to the lower drum, both at the front and the rear. At the front drum, as circulation takes place, there is a continual separation of the heavy undistillable matter which may be contained in the crude, until finally, 100 when there is no more oil remaining in the still body proper, practically all of the heavy bottoms will be contained in the front drums. After distillation has been completed, the bottoms are drained from the front and rear 105 drums through the opening shown. Then as soon as the still has cooled sufficiently, another heated charge is transferred from the treating still into the fractionating still for another run.

Second: In the case of a crude oil (either waxless or containing wax), containing light ends, the crude is first pumped into the fractionating still, or another still similar to it, where it is stripped. The oil is then transferred to the treating still and handled as last described.

Stripping or reducing crude

Stripping or reducing the crude may also be done in the treating still before transferring the charge to the fractionating still, by providing condensers of the form shown on still O on the domes of still B and a vacuum condensing system similar to that shown with still O. For stripping at atmospheric pressure, the wet and dry vacuum pumps may be omitted and the condensate allowed to flow by gravity from the separating tank (which is then vented) to the tanks M, M'. 130

Third: In the case of oil containing wax, the oil is de-waxed before it is re-run.

The re-run

5 The distillate from the first run is pumped to the treating still B, where it is heated (and treated if necessary) to 300° F. and then transferred to still O for fractionating under vacuum. The condensate from the separating tanks flows to pump Y, then passes through the vented look-box L into the line 71. Here the oil is directed into the manifold R through valve 54, or to either tank M or M', through valves 52 or 53. Samples 10 of the cut coming over at any time may be taken from the valve opening 59. The tanks M and M' are measuring tanks, provided with overflow lines to the waste oil tank Z. The vent from look-box L is also arranged to 20 drain as shown into tank Z, so that the oil from pump Y may pass through line 68 and thence through 79 to tank Z should valves 52, 53 and 54 all remain closed any length of time. The measuring tanks have a capacity 25 of approximately 10% of the charge and are calibrated by suitable markings inside so that "cuts" of any desirable quantity may be made on a trial run to determine the points for making the cut in subsequent re-runs of 30 similar distillate to obtain oils of certain flashes or viscosities or to obtain the most economical division, which may be observed through the openings in the top of the tank, with the aid of an extension light. The oil 35 in tanks M and M' is pumped by pump N through line 72 and valve 78 into the manifold R (valve 54 being closed), from which it is run to blending tanks (not shown). The subsequent re-runs of similar distillate 40 are made without the use of the measuring tanks or pump N, the condensate being directed from line 71, through valve 54, into manifold R, thence through valve 55 into tanks T. The tanks T are gauged from time 45 to time and the condensate is directed to different tanks in accordance with the production schedule established by the trial run.

Treating still and setting

50 Referring to Figs. 3, 4, 5 and 6, the treating still 100 is enclosed in a suitable built-up setting 101, which also forms an initial combustion chamber 102 and a space for ducts or passages beneath the still. The ducts are so 55 arranged in this space that the still will be subjected only to indirect heat from the furnace. To this end the setting is provided beneath the still with lower cross-members 103 and upper cross-members 104 located and 60 designed to support an upper tier and a lower tier of duct members, and to provide a duct passage 105 beneath these duct members. The duct members may comprise tubular tiles of oblong cross-section 106 of refractory material. By placing tiles end to end on the

lower cross-members 103, and preferably upright, and in a plurality of lines, side by side, but spaced from each other slightly, a tier of ducts 107 is formed extending longitudinally beneath the still through these lines of tiles. On the upper cross-members 104 a similar tier of ducts 108 is formed through the hollows of similar lines of tiles. The last tile 109 in each lower row and the corresponding tile 110 in the adjacent upper row are specially formed to communicate with each other, and are closed at the end. The furnace is provided with oil burners 111, which may be supplied with air or steam for atomizing, and there is preferably a conventional shutter 70 arrangement for regulating the air admitted to the furnace, in order to obtain the best combustion. Ignition takes place in the furnace 102 and complete burning occurs in the duct 75 passages, forming the combustion chamber, and gases being surrounded by the heated refractory surfaces. The ducts themselves are of such shape as to cause the gases to mix thoroughly, and so further aid in making the combustion more complete. The gases 80 pass from the furnace through the lower tier of ducts 107 and thence forward through the upper tier of ducts 108 into a front chamber 112, from where they pass through two or more large tubes 113 placed in the still body. 85 The connection from the front chamber 112 and rear chamber 114 to the tubes is obtained by ducts 115 of refractory material which do not fit tight, and so provide for an expansion 90 of the still. The tubes themselves are made 95 corrugated for strength and to compensate for expansion. After passing through the tubes of the shell, the cooled gases pass down the rear chamber 114 into an opening 116 in the rear wall, and thence forward, rising between 100 the spaced lines of tiles which form the ducts 107 and 108, constituting the combustion chamber, around the still body and then out the stack opening 117. With this structure I 105 am able efficiently to transmit to the shell, the heat units created by the combustion without at any time subjecting the shell or tubes to unduly high temperature.

As the combustion goes on (it is practically completed in the lower tier of ducts 107) the refractory material of which these ducts are formed will absorb heat from the gases, so that when combustion first starts the gases will have given up a substantial 115 amount of heat before emerging from the upper tier of ducts 108 and entering the tubes 113. Of course, if no method were provided of withdrawing heat from these ducts, they would serve only as a heat reservoir, and very shortly an equilibrium would be established 120 so that the gases emerging from the ducts would be substantially the same temperature as though these ducts were non-absorbent. However, in my arrangement it 125 will be found that the gases which have passed 130

through the tubes 113 will have given up a very large proportion of their heat to the oil, so that when they are re-circulated around the outside of the ducts 107 and 108 they will 5 be withdrawing heat-units from the refractory heat transmitting material and thereby cooling the combustion gases. These heat units will then be carried by convection to the shell and its surrounding casing and be 10 transmitted to the oil, which will be heated rapidly and efficiently but without the application of high local temperatures. In other words, I heat the oil (or the shell in which it is contained) in part directly by convection 15 through the action of the fresh products of combustion and in part indirectly by the convection of the gases which are reheated by contact with the outside of the ducts.

The still body itself is preferably provided 20 with reinforcements 118 against collapsing, entirely on the outside, leaving a clear shell, easily cleaned within. The still body may be suspended from overhead beams 119 by means of rods 120, so that the furnace, combustion 25 chamber and setting walls may be repaired and rebuilt when necessary.

The still body may have conventional man 30 holes 121 and domes 122 extending through the top of the setting and covered with suitable insulation 123.

If desired, the domes 122 may be provided with condensers 124 containing water tubes 125, vapor baffle 126, vapor outlet 127 and liquid outlet 128.

35 Fractionating still and setting

Referring to Figs. 7, 8, 9, 10 and 11, the fractionating still body 200 is provided with reinforcement 201 against collapsing entirely 40 on the outside, leaving a clear shell easily cleaned within. The heads may be either dished in or flat. The body is suspended by means of rods 202 from overhead beams 203 carried on the setting 204. At the end of 45 the setting over the initial combustion chamber 205 and beneath this end of the still tank are drums 206 which communicate with the tank 200 through conduits 207. Beneath the other end of the still are lower drums 208 50 which communicate with the tank through conduits 209. Extending between these drums is a series of circulating pipes or coils 210. Oil enters the lower end of each coil 210 from header H and leaves the open upper end 55 of each coil in the drum 206. During distillation this movement is carried on continuously by the action either of pump P or pump P' as previously described. As a result of this the oil is moved rapidly through 60 the coils in relatively small mass so that it will absorb heat rapidly even though the intensity of the heat transmitted to the coils is substantially below that of the combustion chamber.

65 These coils are welded or expanded into

the drums and are provided with removable return bends 211, and the drums are provided with man hole openings 212 in both ends. The joints of the return bends are made with suitable metal gaskets and clamping means 213, but need not be vacuum tight, as the tubes are welded into the drum, and the vacuum is held on the drums themselves. The clamping means may take the form of yokes secured to the drum walls. For distilling the light ends it has been found unnecessary to use the return bends and pump circulation. The capacity of the pumps is such that the flow of oil will be rapid enough to eliminate carbon deposits in the tubes in practically 70 all cases, however access to the tubes for cleaning purposes is provided for through the man holes in the drums, and through the removable return bends, so that the straight tubes 75 can be easily cleaned.

In accordance with my invention, the oil 80 circulating in the coils 210 is heated indirectly. To this end the coils are disposed between tiers of ducts 214, 215, 216, which may be constructed of pieces of tiling 217 of refractory material having a relatively good heat-transmission capacity, fitted together with a recessed or interlocking joint, which may be cemented. Angle irons 218 are bolted on the tubes 210, which support the end tile pieces. The setting portion 219 supports the tiling from below. Each line of ducts at one end 90 communicates with the corresponding line of the adjacent tier of ducts. For instance, referring to Figs. 7, 8 and 9, the tiles and tiers 95 may be so arranged that combustion gases from the oil burners 220 in furnace chamber 205 pass through an opening 221 into and through the lower lines of ducts 214, then through the second tier of ducts 215, then through the upper tier of ducts 216, through opening 222 and about the still body, from whence they pass through opening 223 into flue 224, and out at the stack 225. Preferably the space 226 beneath the ducts and 100 coils is filled in with insulating material.

105 By this arrangement heat is being continuously absorbed by the walls of the tiles which are of large area and are of a material which is a good transmitter of heat so that they must act as a heat stabilizer or reservoir. From this reservoir heat is being continually drawn to the coils 210 which are in contact with the walls but as the areas of contact are small the flow of heat from these walls to the coils will not be unduly rapid and the intensity of heat to which the oil in these coils is subjected is much less than is the case where the products of combustion come directly in contact with the coils or where the coils are fully imbedded in the furnace walls. However, the fact that the walls are in contact with the pipes and space is provided for a flow of gas between the pipes upwardly at 115 an angle will insure the heat being trans- 120

mitted more rapidly than where radiation alone is relied on.

As a modification of the duct arrangement (see Figs. 10 and 11), there may be an open duct passage 228 provided beneath the tiers of tile ducts, which in this case may be arranged in horizontal lines instead of in inclined lines, as in the previously mentioned arrangement. The arrangement is such that the combustion gases from the furnace 205 pass upwardly through a passage 229 into the upper tier of ducts 230, thence through the second tier of ducts 231, thence into the lower tier of ducts 232, the tiling of these lower ducts having openings 233 in their lower walls, through which the gases pass into the open duct 228, from whence the gases pass through the spaces 234 between the tiles and about the coils 210 located therein. From there the gases pass about the still body and through the opening 223 into flue 224 and stack 225. In this modification the ducts may be formed by means of tubular tiling 235 placed in rows, end to end, the end tiles being closed at one end and opening into a corresponding tile in a corresponding line of an adjacent tier. The tiles may be supported on suitable cross-members 236 provided in the still setting, and blocks 237 between the tiers of tiles. In this modification the action is somewhat different than in the previous case, for here convection is a more important factor, while the contacting surfaces for heat conduction are almost negligible. The products of combustion which have given up a considerable portion of their heat to the walls of the tile ducts pass up around the coils 210 continuously giving up heat to the lower portions of these coils, then absorbing additional heat from the outside walls of the tile ducts and transmitting such heat to other portions of these coils. The residual heat is carried by the gases to the main still body.

The still body has a man hole 238 with an insulating cover 239, and has condensers 240, communicating with the still body through conduits 241, which are covered with suitable insulation 242 where they extend above the setting. The condensers have water tubes 243, connecting with water inlets 244 and outlets 245; vapor baffles 246; vapor outlet 248; and liquid outlet 247.

At the usual rate of driving, practically all of the recoverable heat of combustion is removed from the gases by radiation through the ducts, so that the gases, upon leaving the ducts, have a temperature so low that practically no further transmission of heat can take place from the gases to the oil on account of insufficient "temperature head." However, it will be noted that these gases come in contact with the main body 200 of the fractionating still which will absorb a small amount of heat from the gases, sufficient at least to throw the balance on the safe side

so that the main body of the still will not be radiating heat to the outside air.

This temperature, of course, rises as distillation proceeds, but the same relative conditions exist under uniform rate of evaporation. Now, in order to salvage as much of the heat remaining in the flue gases as practicable, a pre-heater 300 is shown adjoining the still setting at the rear. This pre-heater may be used for warming up the crude charge before it is placed into the treating still or for warming the distillate before it is placed in either still. It may also be used for maintaining the temperature of the oil in the treating still in which it is being held, pending the completion of a run in the fractionating still.

In other words after the oil has been raised to a temperature of 300° F. in the treating still, as outlined previously, the fires may be shut off and this temperature maintained by circulating the oil from the treating still through the pre-heater as shown in conjunction with the fractionating still.

During the pressure treating it would be, of course, hardly practicable to agitate the oil and treating solution by means of air or steam because of the fact that the treating is carried on under pressure. Therefore the oil would be agitated by means of pump circulation as stated, using pump A which would take oil from one end of the still and discharge it near or at the opposite end, thus circulating the oil within the still and thoroughly mixing the oil and treating solution.

As will be noted, the space above the tubes and the tube spaces at either end of the tile are open so that a certain amount of circulation takes place more or less parallel with the tubes, due to temperature.

It is to be understood that my process may be practiced with plants, appliances and apparatus which may differ widely from that described herein. It is also to be understood that as many changes could be made in the above constructional features and process and many widely different embodiments of this invention could be made without departing from the scope thereof, it is intended that all matter contained in the above description or shown in the accompanying drawings shall be interpreted as illustrative and not in a limiting sense.

What I claim is:—

1. In the art of heating oil the steps of heating heat transmitting material by the combustion of fuel and thereby lowering the temperature of the direct products of combustion, and simultaneously withdrawing heat units from said material by contacting a current of relatively cool gas with said material but out of contact with the direct products of combustion, whereby two separate quantities of heated gas are obtained but both at temperatures substantially below the com-

bustion temperature, and contacting both such quantities of gas with a vessel containing oil.

5 2. A process as defined in claim 1 in which the relatively cool gas prior to being contacted with said heat transmitting material to withdraw heat therefrom is brought to a temperature substantially above atmospheric.

10 3. The method of heating oil which comprises the steps of causing combustion of fuel to take place, passing fresh products of combustion in contact with heat absorbent material whereby heat units are given up to such material and the temperature of such gases 15 is reduced, causing such gases to deliver remaining heat units to the material to be heated, passing a gas in contact with said heat absorbent material but out of contact with said fresh products of combustion, 20 whereby heat units are transmitted from said heat absorbent material to said gas, passing said gas in indirect contact with the material to be heated and delivering heat units from said gas to said material.

25 4. The process as defined in claim 3 in which spent products of combustion are used to withdraw heat units from said heat absorbent material after having delivered heat units to the material to be heated.

30 5. The method of heating oil which comprises generating heat by combustion, passing gaseous products of combustion through a heat absorbent structure, partly cooling said fresh products of combustion by separately delivering a portion of the contained heat to the heat absorbent structure, withdrawing heat from the heat absorbent structure and transmitting such heat to the container for the material to be heated largely by 35 convection, whereby a substantial heat differential between the surface of such container and said heat absorbent structure is maintained, and causing the partly cooled 40 fresh products of combustion separately to 45 deliver heat to a different portion of the still from that which is being treated by the heat withdrawn from said heat absorbent structure.

50 6. In combination a still having a plurality of heat absorbing surfaces, an elongated combustion chamber with walls formed of heat transmitting material adapted to absorb heat from fresh products of combustion, 55 means for burning fuel in such chamber, means for bringing products of combustion which have given up a portion of their heat units to said walls into contact with a heat absorbing surface of the still, and thereafter into contact with said heated walls but out 60 of contact with fresh products of combustion, and means for thereafter bringing the reheated products of combustion into contact with another heat absorbing surface of the still.

65 7. A structure as specified in claim 6 in

which the said heat absorbing surfaces of the still are positioned a substantial distance from the heat transmitting walls.

8. The method of distilling petroleum oil without substantial cracking which comprises the steps of generating heat by combustion, contacting the products of combustion with one face of a heat absorbing structure whereby the products of combustion are partly cooled, while contacting a gas with the other face of such heat absorbing structure to withdraw heat units therefrom and causing such gas to contact with a container for the oil to be distilled, and transmitting other heat units from the partly cooled products of combustion to relatively small masses of the oil to be distilled which masses are in rapid movement from and back to a large mass of such oil below the surface level thereof, and withdrawing vapors from the surface of the large mass of oil.

CERTIFICATE OF CORRECTION.

Patent No. 1,834,696.

Granted December 1, 1931, to

RICHARD F. GILDEHAUS, JR.

It is hereby certified that error appears in the printed specification of the above numbered patent requiring correction as follows: Page 8, line 46, claim 5, for the word "treated" read heated; and that the said Letters Patent should be read with this correction therein that the same may conform to the record of the case in the Patent Office.

Signed and sealed this 16th day of February, A. D. 1932.

(Seal)

**M. J. Moore,
Acting Commissioner of Patents.**
